H. R. SHEKERJIAN

BROOM BRIDLE

Filed Oct. 19, 1926

FIG. 1.

H. R. Shekerjian

By *Grace C. Shekerjian*

Attorney

UNITED STATES PATENT OFFICE.

HRANT R. SHEKERJIAN, OF ATLANTIC CITY, NEW JERSEY.

BROOM BRIDLE.

Application filed October 19, 1926. Serial No. 142,721.

My invention relates to improvements in broom bridles and has for its object to provide a device of this character which when placed in operative position on the broom will prevent the broom-straws from spreading and will keep the broom in proper shape, as a whole, whereby it may be used longer.

A further object of the invention is to provide a device of the above-mentioned character having means for securely clamping the device on the broom, so it will not be jarred loose therefrom.

A further object of the invention is to provide a device of the above-mentioned character which is extensible so that it may be adjusted to fit brooms of various sizes.

Another object of the invention is to provide a device of the above-mentioned character which is simple and durable in construction, reliable and efficient in operation and inexpensive to manufacture.

Other objects and advantages of the invention will be apparent during the course of the following description.

In the accompanying drawing, forming a part of this specification and in which like numerals are employed to designate like parts throughout the same.

Fig. 1, is a front elevation of a broom with my invention applied thereto.

Fig. 2, is a perspective view of the invention.

Figure 3 is a horizontal sectional view on the line 3—3 of Figure 1.

Figure 4 is a vertical sectional view on the line 4—4 of Figure 3.

In the drawing, wherein for the purpose of illustration, I have shown a preferred embodiment of my invention, the numeral 5, denotes a conventional type of broom having the usual rows of stitching 6, securing the upper ends of the broom straws together.

Referring more particularly to my invention, the numeral 7 denotes generally a base member composed of separable sections 8 and 9. The section 9 is provided with a series of spaced slots 10, extending transversely of the section, adapted to receive the upstruck lugs 11 extending from the section 8. The outer ends of each section are bent upwardly and slightly reduced, as at 12, to provide lugs 13 which are alined with the lugs 11 and disposed at a slight angle.

The clamping member 14 is composed of two corresponding sections 15 and 16, each being provided with a series of slots 17 corresponding to the slots 10 in the section 9 of the base member. The inner ends of the sections are disposed in overlapping relation, with the slots registering and are fitted over the lugs 11 projecting from the section 8 of the base member. The outer ends of the sections 15 and 16 have their ends bent downwardly, as at 18, adapted to overlap the lugs 13 of the base member when the clamping member is in position. A slot 19 is provided adjacent the bent ends 18 of the clamping member to receive the lugs 13 of the base member.

The upper ends of the lugs 11 and 13 are each provided with a series of vertical aligned openings 20 to receive the locking rod 21. The locking rod extends through the openings of all the lugs, securely holding the clamping member upon the base member and has its end 22 bent at an angle, to provide a handle 23, whereby the locking rod 21 may be readily inserted or removed. A hook 24 has one end adapted for insertion in one of the slots 17 of the clamping member and its opposite end adapted to engage one of the rows of stitching 6 of the broom whereby the device may be adjusted longitudinally of the broom.

To apply the device, the base member is adjusted to fit the width of the broom and the lugs 11 are then pressed through the broom straws. The clamping member is then fitted over the opposite side of the broom and pressed downwardly so that the lugs 11 and 13 project through the slots 17, sufficiently to enable the locking rod to be inserted in the openings of the lugs and when released the expansion of the broom straws will force the clamping member tightly against the locking member, securely fastening the device upon the broom.

It is to be understood that the form of my invention herewith shown and described is to be taken as a preferred example of the same and that certain changes in the size, shape and arrangement of the parts may be made without departing from the spirit of the invention or scope of the claims.

Having thus described my invention I claim:

1. A broom bridle comprising a base member having upstanding lugs provided with openings, a clamping member having a series

of slots adapted to receive the lugs of said base member, and a locking rod insertable through the openings of said lugs.

2. A broom bridle comprising an extensible base member having upstanding lugs provided with openings, an extensible clamping member having a series of slots adapted to receive said lugs, and a locking rod insertable through the openings of said lugs.
- 10 3. A broom bridle comprising a base member having a series of upstanding lugs provided with openings, a clamping member having a series of slots adapted to receive said lugs and a locking rod insertable 15 through the openings of said lugs, said

base and clamping members having overlapping ends.

4. A broom bridle comprising a base member composed of extensible sections, one of said sections having a series of slots adapted to receive lugs bent upwardly from the other section, a clamping member composed of extensible sections, each having a series of slots adapted to receive the lugs of the base member, and a locking rod insertable through 20 25 openings in said lugs, for securing the clamping member in place.

In testimony whereof, I affix my signature.

HRANT R. SHEKERJIAN.
